Application December 31, 1957, Serial No. 49,076

Term of patent 14 years

(Cl. D71—1)

FIG. 1

FIG. 2

FIG. 3

Fig. 1 is front elevational view of a helicopter, showing our new design;

Fig. 2 is a top plan view thereof, the fragmentary showing of four of the five symmetrical blades being for convenience of illustration; and

Fig. 3 is a side elevational view thereof, the fragmentary showing of the forward blades being for convenience of illustration.

The dominant features of our design reside in the portions shown in full lines.

We claim:

The ornamental design for a helicopter, substantially as shown and described.
